LESTER P. BARLOW, OF NEW HAVEN, CONNECTICUT, ASSIGNOR TO MARLIN-ROCKWELL CORPORATION, OF NEW YORK, N. Y., A CORPORATION OF NEW YORK.

WATERPROOF DROP-BOMB.

1,317,612.

Specification of Letters Patent. Patented Sept. 30, 1919.

Application filed February 27, 1918. Serial No. 219,381.

To all whom it may concern:

Be it known that I, LESTER P. BARLOW, a citizen of the United States, residing at New Haven, in the county of New Haven, and 5 State of Connecticut, have invented certain new and useful Improvements in Waterproof Drop-Bombs, of which the following is a specification.

My invention relates to bombs or the like 10 explosive bodies and particularly to that type of bomb which is dropped or launched from an aeroplane and explodes on contact. It is an improvement in certain respects upon the device described in my application 15 Serial Number 195,609 entitled Contact bombs, filed October 9, 1917. In the said application a construction is illustrated in which the detonator of the bomb is normally suspended at a safe distance to the 20 rear of the explosive chamber, and means are provided to release the detonator upon the launching of the bomb. In the preferred form of the device described in said application, the detonator is suspended by means 25 of a pin extending with a sliding fit through the walls of the casing and a portion of the detonator, a strong spring being provided to withdraw the pin from the detonator when the bomb is launched.

30 It is of the greatest importance that such devices should be entirely water and weather proof. My present invention is directed to the provision of means whereby the openings, through which the slideable detonator 35 suspending pin extends, may be effectively sealed at all times until the bomb is launched. I accomplish this object by placing gaskets of suitable packing material about the pin and in contact with the outer surfaces of 40 the bomb casing, adjacent to the openings through which the pin extends. The pin is held in position in the preferred form of my device by a flexible wire which extends through a hole in one end of the pin exterior 45 to the casing, which wire is withdrawn at the moment the bomb is launched. The other end of the pin on the opposite side of the bomb is provided with a head or abutment and a strong spiral spring is coiled 50 about the pin between this abutment and the

gasket located on the adjacent side of the casing. Preferably, washers are interposed between the inner end of the spring and the gasket on one side and between the flexible wire or holding means for the pin and the 55 gasket on the other side of the casing. The result of this construction is that the spring presses outwardly upon the head of the pin constantly, tending to withdraw the pin and pressing inwardly with its inner end upon 60 the adjacent gasket so that both gaskets are compressed strongly against the outer surfaces of the casing and into the openings surrounding the pin, rendering these 65 openings entirely water and weather proof. I have found this construction in practice 70 to be superior to any form of stuffing box through which the pin might extend in which the action of the spring would not tend to exert pressure upon the gaskets or 75 stuffing material.

In order that a clearer understanding of my invention may be had, attention is hereby directed to the accompanying drawing forming part of this application and illustrating one embodiment of my invention. In the drawing the figure represents a central longitudinal section through the rear portion of a bomb embodying my invention, certain parts being shown in elevation. 80

Referring to the drawing, the bomb is represented as having a rear casing member 1, which is joined to a forward casing member 2 containing the explosive chamber 3. The detonator is represented at 4 as extending 85 rearwardly from the guiding tube 5 which is connected with and extends rearwardly from the member 6, having a screw-threaded periphery as shown at 7. This is screw-threaded into a ring 8 which is secured to 90 and suspended from the casing and forms a rear closure for the explosive chamber 3. A booster 9 is integral with or secured to the closure member 6, in the lower portion of which a firing pin is placed to explode the 95 detonator when the bomb strikes its target, as is fully described in my said application referred to.

The detonator 4 is suspended in position, until the bomb is dropped or launched, by 100

means of pin 10 which extends through the opposite walls of rear casing member 1, and through the rear portion 11 of the detonator, with a sliding fit. The pin extends some distance beyond the casing on one side and is provided at its end with an enlargement or spring abutment 12. Preferably, the pin is given an enlarged diameter, as is shown at 13, from the head 12 to a point adjacent the wall 10 of the casing, to form a support for the spiral spring 14, which is coiled about the same. Pin 10 extends a short distance beyond the opposite wall of the casing and is provided with a transverse opening through 15 which extends a flexible wire or cord 15 which constitutes a transversely extending holding means for the pin. This wire 15 is withdrawn at the moment the bomb is launched or dropped from the aeroplane. 20 I have illustrated wire 15 as extending forwardly along the outer surface of the casing of the bomb, this position of the wire being used when the bomb is suspended upside-down in a vertical position from the 25 aeroplane, the bomb righting itself after being launched.

The casing member 1 is preferably provided with bosses 16, 16 on its outer surfaces surrounding the openings through which the 30 pin 10 extends, these bosses forming seats at right angles to the axis of the pin. Gaskets 17, 17 of a fibrous or other suitable packing material, are positioned against bosses 16, 16 so as to closely fit around pin 10. Metallic 35 washers 18, 18 are loosely slipped over the pin so as to press against the outer surfaces of the gaskets 17, 17. When the parts are thus positioned the inner end of spring 14 presses against the adjacent washer 18, while 40 the outer end of the spring presses against the head or abutment 12 at the outer end of the pin. The outward pressure of the spring upon the abutment 12 tends constantly to withdraw the pin from the bomb and consequently causes the wire 15 at the other end 45 of the pin to constantly press the adjacent washer 18 against the adjacent gasket 17 so that the latter is constantly pressed against the adjacent boss 16. At the same time the inner end of spring 14 constantly presses the adjacent washer 18 inwardly against the adjacent gasket 17 and accordingly presses the latter constantly against the adjacent boss 16. Accordingly, both 55 gaskets are constantly compressed against the outer faces of the casing surrounding the pin openings with the result that a tight and weather-proof joint is effected at each opening. When, however, wire 15 is withdrawn and spring 14 expands, the pressure upon gaskets 17 is removed so that the pin may move easily through the same as it is ejected from the bomb by the spring. The result of this action is, of course, that the

detonator is allowed to drop through tube 65 5 into position such that the bomb may be exploded when it hits its distant target.

What I claim is:

1. In a bomb or like body, the combination of a casing, a detonator therein, a pin 70 adapted to extend with a sliding fit through openings in the opposite walls of said casing, and through a portion of said detonator, to normally suspend the latter, said pin having an abutment at one end, transversely extending holding means, adapted to be withdrawn when the bomb is launched, mounted at the other end of the pin, packing material surrounding said pin, between said holding means and the casing, packing material surrounding said pin, positioned against the opposite outer wall of the casing, and a 75 spring mounted to continuously press said last named packing material against the casing, and also to press outwardly against said abutment.

2. In a bomb or like body, the combination of a casing, a detonator therein, a pin adapted to extend with a sliding fit through openings in the opposite walls of said casing, and through a portion of said detonator, said pin having an abutment at one end, a wire 80 extending through an opening at the other end of the pin, adapted to be withdrawn when the bomb is launched, packing material between said wire and casing, packing material positioned against the outer side of the opposite casing wall, about the opening therein, and means for constantly and resiliently pressing said last named packing material against the casing, and said abutment 85 in the opposite direction.

3. In a bomb or like body, the combination of a casing, a detonator therein, a pin adapted to extend with a sliding fit through opposite lateral walls of said casing, adjacent the rear end thereof, and through a portion of said detonator, to normally suspend the latter, said pin having an abutment at one 105 end and a transverse opening, adjacent the other end, a connection extending through said opening, adapted to be withdrawn when the bomb is launched, gaskets of packing material surrounding said pin, positioned against the outer walls of the casing, a 110 washer interposed between one of said gaskets and said connection, a washer positioned against the outer surface of the other gasket, and a spiral spring surrounding said pin between, and exerting pressure upon, 115 said last named washer and said abutment.

4. In a bomb or like body, the combination of a casing, a member held therein, a pin adapted to extend with a sliding fit through openings in the opposite walls of said casing, and slidably holding said member, said pin having an abutment at one end, transversely extending holding means, adapted 125

to be withdrawn when the bomb is launched, mounted at the other end of the pin, packing material surrounding said pin, between said holding means and casing, packing material 5 surrounding said pin, positioned against the opposite outer wall of the casing, and a spring mounted to continuously press said last named packing material against the

casing, and also to press outwardly against said abutment.

10

This specification signed and witnessed this 16th day of February, 1918.
